(57) **CLAIM**

The ornamental design for a camera arm, as shown and described.

DESCRIPTION

FIG. 1 is a perspective of the camera arm.

FIG. 2 is a bottom view of the camera arm.

FIG. 3 is a top view of the camera arm.

FIG. 4 is a right side view of the camera arm.

FIG. 5 is a left side view of the camera arm.

FIG. 6 is a front end view of the camera arm; and,

FIG. 7 is a back end view of the camera arm.

The portions of the camera arm in broken lines are shown for illustrative purposes only and form no part of the claimed design.
